UNITED STATES PATENT OFFICE.

GEORGE W. GOSS AND CHARLES E. GOSS, OF BALTIMORE, OHIO.

GATE.

1,087,656.

Specification of Letters Patent. Patented Feb. 17, 1914.

Original application filed September 26, 1912, Serial No. 722,554. Divided and this application filed December 20, 1912. Serial No. 737,914.

To all whom it may concern:

Be it known that we, GEORGE W. Goss and CHARLES E. Goss, citizens of the United States, residing at Baltimore, in the county 5 of Fairfield, State of Ohio, have invented a new and useful Gate, of which the following is a specification.

The present invention appertains to gates, the present application being a division of the application filed September 26, 1912, Serial No. 722,554. It is the object of the present invention to provide a novel adjusting mechanism for supporting the free end of a gate in various positions above the ground, and to prevent the free end of the gate from sagging.

With the foregoing and other objects in view which will appear as the description proceeds, the invention resides in the combination and arrangement of parts and in the details of construction hereinafter described and claimed, it being understood that changes in the precise embodiment of invention herein disclosed can be made 5 within the scope of what is claimed without departing from the spirit of the invention.

The device has been illustrated in its preferred embodiment in the accompanying drawing wherein:

0 Figure 1 is an elevation of the gate embodying the present invention. Fig. 2 is an enlarged sectional detail taken on the line 2—2 of Fig. 1.

Referring specifically to the drawing, the present gate embodies a plurality of spaced rails 4, a plurality of duplicate stiles 5 receiving the rails therebetween, and the duplicate diagonal braces 5' inclined away from the hinged end of the gate, the stiles 5 and braces being connected by securing members 6 so as to clamp the rails securely therebetween. The gate structure may be varied, it being understood that the adjusting mechanism is applicable to various gates 5 and is not limited to the particular gate structure shown and described. The stiles at the hinged end of the gate are preferably inclined slightly away from the post 7 to which the gate is hinged, the corresponding ends of the rails are also similarly cut away so as to permit the gate to be readily raised.

In order to hinge the gate to the post 7, the post is provided with the upper and lower pintles 8 and 8', respectively, an approximately horizontal rod 9 being disposed

between the upper rails and passing between the respective duplicate stiles, and also having an eye 10 at its outer end engaging the upper pintle 8, while a strap or hanger 9' is secured between two lower rails 60 and is provided with an eye 10' loosely engaging the lower pintle 8' to permit the gate to tilt. The rod 9 is adjustably secured to the gate, so as to permit the free end of the gate to be raised or lowered to suit 65 the circumstances.

In order to effect the adjustable connection between the hanger rod 9 and the gate structure, a gripping member 11 is mounted on the braces 5' between the upper rails, 70 this gripping member being connected to the inner end of the rod 9. The gripping member comprises the side pieces 12 having their lower ends 13 offset toward each other and connected by a pin 14, which pin is engaged by an eye 15 formed at the inner end of the rod 9. The side pieces 12 are connected by pins 16 above and below the braces 5', the said pins being adapted to grip the braces, when the side pieces are 80 swung.

The rod 9 is guided between the corresponding stiles and braces, and by sliding the gripping member 11 on the braces, the free end of the gate may be raised or lowered, the tendency of the gate to gravitate serving to bind the gripping member on the braces so as to maintain the gate in its adjusted position. This adjustment of the gate is of advantage for several reasons, 85 which will be evident to those versed in the art, the primary one being to prevent the free end of the gate from sagging. The gate is also free to swing in either direction, the present improvements not encumbering 95 the gate in any manner, but on the other hand, being compact, simple, durable and efficient.

A suitable latch 17 is preferably carried by the free end of the gate for engaging the post 18 at the free end of the gate when the gate is closed, as is well known and of no particular moment in the present case.

Although the present adjusting mechanism is preferably employed with the gate structure forming the subject matter of the aforementioned application, it is apparent that the adjusting mechanism may be employed in connection with other gate structures, with but slight alterations.

Having thus described the invention what is claimed as new is:—

1. In combination, a post, a gate, a hanger carried by the gate and loosely connected to the post, the gate including rails and an inclined member secured thereto, a gripping member adjustable on the said inclined member, and a hanger rod disposed between certain rails connected to the gripping member and connected loosely to the post for supporting the gate.
2. In combination, a post, a gate, a hanger carried by the gate and loosely connected to the post, the gate including a brace inclined away from the hinged end of the gate, a gripping member adjustable on the brace, and an approximately horizontal hanger rod pivoted to the lower end of the gripping member and connected loosely to the post.
3. In combination with a gate structure including duplicate braces inclined away from the hinged end of the gate, a gripping member mounted on the braces, and a hanger rod passing between the braces and pivoted to the lower end of the gripping member.
4. In combination with a gate structure including spaced rails, and duplicate stiles and braces secured to the respective sides of the rails, the braces being inclined away from the hinged end of the gate, a gripping member mounted on the braces between two

upper rails, and a hanger rod passing between the said rails and then between the stiles, the rod being connected to the gripping member.

5. In combination with a gate structure including spaced rails, and duplicate stiles and braces secured to the respective sides of the rails, the braces being inclined away from the hinged end of the gate; a gripping member mounted on the braces between two upper rails, and a rod passing between the said rails and between the stiles and braces, the inner end of the rod being pivoted to the lower end of the gripping member.

6. In combination with a gate structure including duplicate braces inclined away from the hinged end of the gate, a gripping member mounted on the braces and comprising side pieces and pins connecting the side pieces above and below the braces to grip the same, the lower ends of the side pieces being offset toward each other, and a hanger rod having its inner end pivoted between the offset ends of the side pieces.

In testimony that we claim the foregoing as our own, we have hereto affixed our signatures in the presence of two witnesses.

GEORGE W. GOSS.
CHARLES E. GOSS.
